UNITED STATES PATENT OFFICE

RAY SCULTHORPE, OF SHARPSVILLE, PENNSYLVANIA, ASSIGNOR TO SHENANGO-PENN MOLD COMPANY, OF SHARPSVILLE, PENNSYLVANIA, A CORPORATION OF PENNSYLVANIA

DRYING SAND MOLDS

Application filed November 17, 1928. Serial No. 320,196.

This invention relates to the drying of sand molds and more particularly to the drying of sand molds for casting metal. It contemplates an apparatus for more effectively utilizing the drying medium used in drying the molds than has heretofore been possible, and a method of drying such molds.

Sand molds for use in metal casting are first prepared by packing sand in a suitable flask or container using a suitable pattern or smoothing device, and then subjecting the packed sand to the action of a drying medium for the purpose of driving out the contained moisture and preparing the sand walls for the reception of the molten metal. Ordinarily in drying molds they are subjected to the action of hot gases, which may be the products of combustion from a furnace. The drying gases are conducted into the presence of a mold and are allowed to flow in proximity thereto, heating the sand walls and abstracting the moisture therefrom.

Usually the molds are placed either in a drying oven or upon a rack, provision being made below the molds for the admission of drying gases. Ordinarily the respective molds are placed substantially above openings in the bottom of the rack, the drying gases emerging from such openings and passing in proximity to the molds.

When the molds to be dried are of small size and so positioned that the drying gases emerging from the conduit conveying them into the presence of the mold must necessarily impinge thereagainst, the drying is effectively accomplished. However, when the molds are of large size or of such shape that one or more of the sand surfaces cannot be placed directly in the path of the drying gases, a marked loss in drying efficiency results. Gaseous bodies have a tendency to stratify and flow in segregated masses, particularly in cases where the temperature of a flowing gaseous body is materially different from the temperature of the surrounding atmosphere. A body of drying gases emerging from the conduit conveying such gases into the presence of a mold has a natural tendency to stratify or segregate and to flow in a direct path in the direction of least resistance. Ordinarily this

direction is upwardly because the temperature of the surrounding atmosphere is materially lower than that of the drying gases.

In the case of any but the smallest and simplest molds the drying gases may impinge against a small portion of the sand surface thereof, but will usually rise upwardly and tend to stay away from the sand surface. For example, this condition is quite marked in the case of large sized sand surfaced ingot molds. Such molds are normally placed over drying gas outlets so that the gases emerge in the interiors thereof. A natural chimney effect is created in such a mold and the gases take the path of least resistance, namely, straight upwardly through the center of the mold without coming into intimate contact with the sand walls. Only a small proportion of the available drying efficiency is utilized.

I provide an apparatus and method for drying sand molds adapted to obviate the disadvantages above noted and to more efficiently and effectively dry the sand than has heretofore been possible. I provide a source of gases, a conduit for conducting the gases into the presence of a mold wall, and means positively directing the gases into a path of travel along the mold wall, whereby to prevent a stream of substantially segregated or stratified gases from flowing past the mold wall with little drying effect. I further provide a device for drying said mold walls comprising a deflecting means having a deflecting surface and having supporting means spacing the deflecting surface from the means upon which the deflecting means is supported. I still further provide a method of drying sand mold walls comprising introducing drying gases into the presence of a wall and directing the path of the gases therealong. Other objects and advantages will become apparent as the following description of a present preferred embodiment of the invention proceeds.

In the accompanying drawings, I have shown a present preferred embodiment of the invention wherein

Figure 1 is a cross sectional view through a mold drying apparatus having a mold in place thereon;

Figure 2 is a top plan view of the apparatus shown in Figure 1; and

Figure 3 is a detail perspective view of a device for use in drying molds.

Referring more particularly to the drawings, reference numeral 2 designates generally a foundation or floor upon which is constructed a flue or gas passageway 3. The flue 3 may be one of a number connected to a furnace or other suitable source of drying gases. It is provided at intervals in its upper wall with openings 4 for permitting the escape and upward flow of the drying gases contained therein. The top surface of the flue serves as a support or base upon which are placed flasks 5 having sand molding surfaces 6. The sand is first introduced and suitably packed or rammed within the flask, after which the flask is placed on the rack or flue for drying. The mold is provided with a down pouring gate 7 and an in pouring gate 8.

Resting upon the rack and preferably disposed directly above an opening or conduit 4 is a deflecting device designated generally by reference numeral 9. This device comprises a lateral deflecting surface 10 and a plurality of legs 11 spacing the surface 10 from the top of the rack. The device is further provided with a laterally extending conduit 12, one extremity of which opens beneath the deflecting surface 10 and preferably substantially above the conduit 4. The outward extremity of the conduit 12 extends toward and into proximity with the in-pouring gate 8. The inner extremity of the conduit 12 is beveled, as shown in Fig. 1, thus to provide for the reception of as large a quantity of drying gases as is practicable.

The drying gases rising upwardly through the opening 4 in the rack have a natural tendency, as above explained, to stratify and rise straight upwardly without coming into intimate contact with the sand walls of the mold by reason of the interposition of the deflecting device 9. However, the stream of drying gases is deflected or interrupted and caused to segregate and flow laterally in all directions. Due to the substantial velocity of the gases, this lateral flow causes them to impinge with considerable force against the sand walls, and as their natural tendency is thereafter to rise straight upwardly, they will rise in substantially intimate contact with the walls, thereby most effectively drying them.

Heretofore great difficulty has been experienced in drying the pouring gates inasmuch as the inner extremity of the in gate is near the bottom of the mold and the gases have an opportunity to move past such gate before moving laterally to a sufficient extent to enter it. In many instances in an effort to completely dry the gates to enable the metal to be poured, the sand walls have been badly

burned, necessitating the putting aside of the mold without being used. This disadvantage is overcome by the provision of the device 9 having a laterally extending conduit 12 which directs a substantial volume of the drying gases toward and into proximity with the pouring gate. The gases which do not pass through the conduit 12 are mushroomed or laterally deflected in all directions and pass upwardly along the inner sand wall 6. Thus a most effective and quick drying of the mold is accomplished.

When molds without pouring gates are being dried, the conduit 12 may be omitted from the deflecting device 9, if desired, or in case a portion of the sand surface is of greater thickness than another portion, the conduit 12 may be utilized to convey a substantial volume of dry gases into proximity with the thicker portion. The deflecting device is adjustable to cause a greater proportion of the gases to be directed as may be desired, and is very easily removed by merely lifting it with a hook or other suitable tool.

While I have shown and described a present preferred embodiment of the invention, I wish it distinctly understood that the same is not limited thereto, but may be otherwise embodied and practiced within the scope of the following claims.

I claim:

1. The combination of a source of gases for drying sand mold walls, means for conducting the gases into the presence of a mold wall, and an adjustable and removable baffle device for deflecting the gases as they are introduced into drying relationship with the mold wall.

2. The combination of a source of gases for drying sand mold walls, means for conducting the gases into the presence of a mold wall, and means for directing the gases toward the mold wall, such means having provision for directing at least a portion of the gases toward a localized portion of the mold wall.

3. The combination of a source of gases for drying sand mold walls, means for conducting the gases into the presence of a mold wall, and means for directing the gases toward the mold wall, such means having a conduit for directing at least a portion of the gases toward a localized portion of the mold wall.

4. The combination of a source of gases for drying sand mold walls, means for conducting the gases into the presence of a mold wall, having a pouring gate therein, and means for positively directing at least a portion of the gases toward and into proximity with the gate.

5. The combination of a source of gases for drying sand mold walls, means for conducting the gases into the presence of a mold wall having a pouring gate therein, and

means for directing the gases toward the mold wall, such means having provision for directing at least a localized portion of the gases directly toward the gate.

6. The combination of a source of gases for drying sand mold walls, supporting means for a mold having a conduit therein for conducting the gases into the presence of a mold wall, and a removable deflector resting on the supporting means in the path of the gases.

10 7. In apparatus for drying sand mold walls, a deflecting means having a deflecting surface and having a conduit extending generally laterally from such surface.

15 8. In apparatus for drying sand mold walls a deflecting means having a deflecting surface, legs spacing the deflecting surface from the means upon which the deflecting means 20 is supported, and a conduit extending outwardly therefrom.

25 9. In apparatus for drying sand molds, a deflecting means adapted to be interposed in the path of drying gases, such means having a surface adapted to deflect the gases substantially laterally and having means for conducting a portion of the gases in a desired localized direction.

30 10. In a method of drying a sand mold having a pouring gate, the steps comprising introducing drying gases into the presence of the mold, deflecting the gases toward the mold, and conducting a quantity of gases toward and into proximity with the gate.

35 11. In testimony whereof I have hereunto set my hand.

RAY SCULTHORPE.
